UNITED STATES PATENT OFFICE.

WILLIAM G. CRAIGEN, OF ABERDEEN, SCOTLAND.

GAME.

Application filed March 9, 1921. Serial No. 451,026.

To all whom it may concern:

Be it known that I, WILLIAM G. CRAIGEN, a subject of the King of England, residing at Aberdeen, N. B. Scotland, have invented 5 certain new and useful Improvements in a Game, of which the following is a specification.

This invention relates to games and more particularly to an amusement device simulating a yacht race.

The primary object of the invention is to provide a game board having pieces to simulate yachts and including permanent magnets adapted to be held in the hands 15 of the players whereby the game pieces may be moved on the surface of the game board to simulate the movement of racing yachts.

Other objects of the invention will appear upon consideration of the following 20 detail description and accompanying drawings, wherein:—

Figure 1 is a perspective view of the device constructed in accordance with my invention and showing the manner of holding 25 the magnet so as to manipulate the game piece.

Figure 2 is a transverse section through the game board,

Figure 3 is a view of one of the magnets 30 used in playing the game and

Figures 4 and 5 are detail views of two different forms of game pieces constructed to simulate racing yachts.

Referring to the drawing by numerals, a 35 substantially rectangular frame 1 is provided which includes the parallel frame bars 2 and 3 and the end frame bars 4 and 5, with a longitudinally centrally located supporting bar 6 extending lengthwise 40 through the frame. The frame is properly fastened together and a top covering 7 is mounted on the frame by suitable adhesive. Any suitable material may be employed for the top covering 7 but it has been found 45 that tracing cloth or label cloth is best adapted for the purpose thereby providing a smooth surface over which the game pieces may move. Pivotally mounted legs 8 are mounted on the frame so that they 50 may be extended to support the frame when the game is being used, and may be folded into the frame when the game is not in use or is being packed for shipment.

As shown in Fig. 4 one of the game pieces 55 is constructed of cardboard and is shaped

to simulate a yacht the portion 9 representing the sails of the yacht and it will be understood that this portion may be suitably inscribed with lines and coloring to secure the desired effect. The base member 10 60 consists of a strip of magnetic material folded upon itself at each end and having upturned portions 11 between which the lower marginal edge of the portion 9 is secured. The portion 10 therefore forms a metallic base adapted to move over the surface of the game board and it will be noted that the base is considerably greater in length than in width and extends transversely with respect to the portion 9 of the 70 game piece. The permanent magnet 12 is of the usual type and is preferably magnetized only enough to attract the base 10 when the terminals of the magnet are in close proximity to the base so that there 75 will be no force exerted on the base by the magnet unless the latter is held close to the bottom surface of the covering 7 as shown in Fig. 1.

The top surface of the covering 7 is inscribed to provide two race courses having the starting and finishing points at one end, and a buoy at the opposite end around which the game pieces are to pass while the race is being conducted so that it will be 80 necessary to move the game pieces upwardly and downwardly of the course.

As shown in Fig. 5 a slightly modified form of game piece is provided which is similar to the game piece shown in Fig. 4 85 except that the base member 13 is of heavier construction and is narrower lengthwise of the sails 9' and thus requires a magnet to be held at right angles to the position shown in Fig. 1 before the base will be attracted to the magnet when it is applied to the game piece. This requires the game piece to be moved in a criss cross manner across the course when the race is being conducted thus simulating the movement 95 known as "tacking".

Any suitable set of rules may be employed to play the game and it will be obvious that modifications may be made in these rules as desired to make the game more entertaining 100 and amusing.

Minor changes may be made in the details of construction without departing from the spirit of the invention or the scope of the claim hereunto appended.

What is claimed is:—

A game of the character described comprising a rectangular frame having a relatively thin covering mounted on the top thereof, said frame adapted to be supported in a horizontal plane and high enough to permit the hand of the player to be extended beneath the frame, pivotally mounted folding legs mounted on the frame, game pieces shaped to simulate yachts, base members each consisting of a strip of metallic material folded upon itself at each end and having up-turned portions between which the lower marginal edge of a game piece is secured, permanent magnets designed to at-

tract the base members of said game pieces, the top surface of the covering being inscribed to provide a race course having the starting and finishing points at one end, said metallic bases being attracted to the magnets for moving the game pieces when the magnets are moved beneath the covering. 20

In testimony whereof, I have affixed my signature in the presence of two witnesses. 25

WILLIAM G. CRAIGEN.
